KNITTING MACHINE

Frank G. Weisbecker, Glenside, Pa., assignor to
 Hosiery Patents Incorporated, Lansdale, Pa., a
 corporation of Pennsylvania

Application March 5, 1942, Serial No. 433,511

11 Claims. (Cl. 66—126)

The invention relates to improvements in knitting machines and particularly to improvements in yarn carriers and parts thereof for use in straight knitting machines such as those which produce full-fashioned hosiery blanks.

For a showing of a conventional yarn carrier and its use on a straight, full-fashioned hosiery knitting machine, reference may be made to the Patent No. 2,014,341 which issued on September 10, 1935.

It is an object of this invention to provide a novel and improved form of yarn carrier which is relatively simple and inexpensive to manufacture, which is of relatively simple construction, and which is both durable and efficient in use on a knitting machine.

A further object is to provide a novel and improved form of removable yarn guide tube for yarn carriers.

Still another object is to provide a yarn carrier with a readily replaceable yarn guide tube of resilient construction.

A still further object is to provide a yarn carrier with a resilient yarn guide tube, the resilience of which facilitates insertion and replacement of the tube in the carrier arm as well as avoids damage in event of the tube striking an obstruction during use.

Another object is to provide a yarn carrier with a removable, resilient yarn guide tube, which is so constructed and mounted as to provide free feed of yarn by the carrier and to provide a carrier of minimum thickness at its yarn discharge end.

Other objects and advantages of this invention will be apparent from the following description, the appended claims, and the accompanying drawing, in which:

Figure 1 is a perspective view of a yarn carrier embodying this invention and assembled ready for use on a straight, full fashioned hosiery knitting machine such as shown in Figure 1 of Patent No. 2,014,341, dated September 10, 1935.

Figure 2 is an enlarged detail view of the lower end of the yarn carrier of Figure 1, the yarn guide tube being illustrated in a position assumed during its insertion or withdrawal.

Figure 3 is an enlarged detail front elevational view of the lower end of the carrier of Figure 1.

Figure 4 is a view corresponding to Figure 3, but with the yarn guide tube omitted in Figure 4.

Figures 5, 6 and 7 are cross-sectional views taken on lines 5—5, 6—6 and 7—7 respectively of Figure 3.

Figure 8 is an enlarged detail view of the yarn guide tube of Figures 1 and 10.

Figure 9 is a top plan view of the yarn guide tube of Figure 8.

Figure 10 is a perspective view of another yarn carrier embodying this invention.

Figure 11 is an enlarged detail, front elevational view of the lower end of the carrier of Figure 10.

Figure 12 is an enlarged perspective view of the lower end of the carrier of Figure 10, the yarn guide tube being omitted in Figure 12.

Figure 13 is a cross-sectional view taken on line 13—13 of Figure 11.

The yarn carrier of Figure 1 comprises a carrier arm 1 and a removable guide tube 2. The carrier arm 1 is widest at its upper end 3 which is to be secured to a carrier bar (not shown) of a conventional knitting machine. As the arm 1 is preferably of relatively thin material, its upper end 3 has a reinforcing plate 4 secured thereto as by welding. Threaded openings 5 are formed in the arm end 3 and the plate 4 to receive threaded bolts (not shown) for securing the carrier arm 1 to a knitting machine carrier bar (not shown). The plate 4 may be secured to either the front or back face of the carrier arm end 3. The carrier arm 1 preferably is of tapered form so that its thinnest portion is at the lower end which supports the tube 2. The lower end of carrier arm 1 is also tapered to its opposite edges as shown by Figures 5, 6 and 7. Along the center line of the lower carrier arm, the arm thickness is preferably of substantially the same dimension as the external diameter of the yarn guide tube 2. Thus the external diameter of the tube 2 determines the preferred maximum thickness for the lower carrier arm end, and interference of the yarn carrier with other yarn carriers during use on a knitting machine is minimized. It is to be noted that conventional straight knitting machines have as many as seven or nine yarn carriers for use in knitting a single stocking blank and that the lower ends of the carriers travel in closely spaced, parallel relation, the individual carriers having reciprocating movement and traveling in an edgewise direction. The lower end edge 6 of the carrier arm 1 is of curved configuration to provide space for free flexing movement of the protruding end of the guide tube 2. A bore or passage 7 extends along the center line of the arm 1 from the end edge 6 to an eye or opening 8. The diameter of the bore 7 is preferably such as

55 to provide a free sliding fit for the guide tube 2.

Where the center of the carrier arm 1 is thicker than the diameter of the bore 7, the process of forming the bore 7 will not result in a break in the front or rear faces of the carrier arm. Where the diameter of the bore 7 is substantially the same as the thickness of the arm portion in which the bore 7 is formed, the front and rear faces may each be slidably separated along a narrow line as indicated at 9. The opening 8 is relatively narrow so as to avoid weakening of the carrier arm and is preferably not substantially greater in width than the external diameter of the guide tube 2. The upper end of opening 8 terminates adjacent and below the bend 10 in the carrier arm 1. Where the carrier arm 1 is of sufficient thickness, the opening 8 may be in the form of a recess in one face of the carrier arm 1 to thereby leave the reverse carrier arm face unbroken. A yarn guide groove 11 extends along the upper face of the carrier arm 1 and terminates at the opening 8. A recess or recesses 12 are formed in a face of the carrier arm 1 and extend laterally from opposite sides of the upper end of the opening 8. The bottom of the recess or recesses 12 may be curved for a purpose to be described.

The guide tube 2 comprises an apertured tip 15, a resilient tubular portion 16, and an apertured latch-like member or projection 17 which parts (15, 16 and 17) may be secured in assembled relation as by welding. The resilient tubular portion 16 is preferably formed of coiled wire and may comprise both round wire and flat wire as shown by Figure V of Patent No. 2,101,801, dated December 7, 1937. The tip 15 is preferably of such material and character as to be resistant to wear due to yarn passing therethrough. The latch-like member or pin 17 is shaped to fit the recess or recesses 12, one side of the pin 17 being curved to fit the curved recess bottom, and the other side being shaped so as to lie flush with the front face of the carrier arm 1. The tubular portion 16 is of such length that, with the pin 17 in the recess or recesses 12, it (16) extends along the opening 8 through the bore 7 and beyond the outer end of the bore 7 to support the tip 15 in a position beyond the extreme end of the carrier arm 1 (see Figure 3, for example). In the event the projecting tube end including the tip 15 strikes an obstruction during use of the yarn carrier on a straight knitting machine, the projecting tube end may yield due to the flexibility of the tubular portion 16. When the obstruction has been passed, the deflected tube end will return to normal yarn feeding position due to the resiliency of the tubular portion 16. In its yielding movements, the projecting guide tube end having the tip 15 may move in the space defined by the curved end edge 6 of the carrier arm 1.

The yarn guide 2 may be readily removed from the carrier arm 1 by lifting the projection 17 from the recess 12 and sliding the tube endwise until the tip 15 is withdrawn from the bore 7. The tube removal may be accomplished with the use of tweezers. The tweezers may grip the tubular portion 16 adjacent the pin or projection 17. The tube 2 may be inserted in place in the carrier arm 1 by inserting the tip 15 in the opening 8 and in the upper end of the bore 7. When endwise force is exerted on the guide tube 2, it will slide along the bore 7. As the pin 17 assumes a position opposite the recess or recesses 12, the pin 17 is released and, due to the resiliency of the flexible tube portion 16, is snapped into the recess or recesses 12. The resiliency of the tu-

bular portion 16 opposes any tendency of the pin 17 to move out of its recess 12. The pin 17 and its recess 12 thus provide a latching device for retaining the guide tube 2 and carrier arm 1 in assembled relation. This latching device also prevents longitudinal movement of the guide tube 2 along the carrier arm 1. The guide tube 2 is thus securely held in proper yarn laying position on the carrier arm 1. The resiliency of the tubular portion 16 opposes any tendency of the projection 17 becoming unseated due to jarring of the yarn carrier while in use on a straight knitting machine. The resiliency of the tubular portion 16 also permits it to yield or flex and thereby facilitates the release of the pin 17 from its recess 12 and the withdrawal of the guide tube 2 by a knitting machine operator or attendant.

The curved shape of the pin 17 and the bottom of its recess 12 permits the pin 17 to adjust its latching position under the influence of the resilient tubular portion 16 so that the tubular portion 16 may automatically assume a straight line position.

The yarn carrier of Figure 10 comprises a yarn carrier arm 21 and a yarn guide tube 22. The yarn carrier arm 21 is straight at its lower end which, therefore, does not have the bend 10 of the carrier arm 1. The upper end of the carrier arm 21 is provided with openings 23 whereby the carrier arm 21 may be secured to a carrier bar of a conventional knitting machine by means of screw and nut connections. Thread or yarn in passing along the carrier of Figure 10 is guided by an aperture 24, a loop 25, a groove 26, and the tube 22. This tube 22 is of the same construction as the tube 2 of Figures 1 and 8, for example. The tube 22 is supported in a bore 27 which is formed in the arm 21 similarly to the forming of the bore 7 in the arm 1 of Figure 1. The lower end of the carrier arm 21 is somewhat thinner than the lower end of the carrier arm 1. Due to this reduced thickness of the carrier arm 21, the bore 27 is open at its sides so as to be of sufficient diameter to accommodate the tube 22. A narrow opening 28 in the arm 21 extends from the lower end of the groove 26 to the inner end of the bore 27. The face of the arm 21 is grooved or recessed at 29 to provide a seat or keeper for the pin 17 of the guide tube 22. The groove 26 and the tube 22 are substantially in alignment (Figures 10 and 11) so that yarn passing therethrough will travel in substantially a straight path. The recess or recesses 29 extend laterally from the opening 28 and are positioned intermediate the opposite ends of the opening 28 as shown, for example, in Figure 12.

The carrier arms 1 and 21 are illustrated as having the same shape for their lower end edges and the same general tapered shape for their lower ends.

The guide tube 22 is removed from and inserted in the carrier arm 21 in substantially the same manner as explained with regard to the yarn carrier of Figure 1. When the carrier of Figure 10 is used on a knitting machine, its tube 22 operates in the same manner as described with respect to the tube 2.

In both of the carriers illustrated in Figures 1 and 10, the carrier arm (1 or 21) is preferably of rigid construction with its lower end providing a substantially inflexible support for its guide tube. The substantial width of the carrier arm sections at each side of a guide tube contribute to the rigidity of such sections even though they are separated along the center line of the car-

rier arm. The bore of each carrier arm, therefore, remains fixed to provide a free sliding fit with its guide tube, while avoiding objectionable lateral movement of the guide tube portion within the bore.

The resiliency of the removable yarn guide tube performs three functions. The resiliency permits deflection of the tube tip in event of its striking an obstruction and insures return of the tip to normal position when the obstruction has been passed. The resiliency opposes any tendency of the tube latch or pin to accidentally rise out of its recess or pocket. The resiliency also permits the tube to be readily flexed when an attendant inserts or replaces a yarn guide tube in a carrier arm. Thus assembly of the tube and its removal is accomplished with the aid of the inherent resiliency of the tube itself. The carrier arm may, therefore, be of rigid construction and provide a steadier support for its guide tube.

The carrier arms may be relatively inexpensive and may be cast in the form shown or formed from blanks with the grooves, openings and bores formed in any suitable manner. The bore which receives the central section of a guide tube may be formed in a drilling operation.

The foregoing is to be understood as illustrative, since this invention includes all modifications and embodiments coming within the scope of the appended claims.

I claim:

1. In a yarn carrier for knitting machines, the combination comprising a relatively rigid yarn carrier arm, a removable guide tube supported by said arm and having an intermediate portion thereof of resilient construction in the form of coiled wire, and a latching device for retaining said tube and said carrier arm in assembled relation, said tube being removable from said arm by flexing said tube to disengage said latching device and sliding said tube endwise.

2. In a yarn carrier for knitting machines, the combination comprising: a carrier arm and a removable yarn guide tube carried by said arm; said tube having a laterally extending projection adjacent an end thereof and having a portion of the tube length of resilient construction, said resilient portion extending from said projection toward the far end of the tube; said carrier arm having a bore extending inwardly from an end edge thereof and adapted to receive said tube, at least a portion of the length of said bore having a shape and diameter corresponding substantially to the shape and outer diameter of a corresponding portion of the length of said tube, said carrier arm having a recess above said bore portion to receive said projection with said last-named tube portion disposed in said bore portion, said resilient tube portion being adapted to be flexed to permit withdrawal of said projection from said recess and removal of said tube endwise through said bore.

3. In a yarn carrier for knitting machines, the combination comprising: a carrier arm having a bore extending inwardly from an end edge thereof, and a recess in one face of the arm, and positioned above the inner end of said bore, the bottom of said recess curving in a direction transversely of said arm; and a guide tube fitted in said bore and having a latch-like portion disposed in said recess, said latch-like portion being shaped to conform substantially to the

5 curved shape of said recess, said guide tube having a resilient portion tending to adjust said latch-like portion in said recess to maintain the tube in a substantially straight-line position while the tube is held against longitudinal movement by engagement of said latch-like portion and said recess, said resilient portion being adapted to be flexed to withdraw said latch-like portion from said recess in removing said tube from said bore and from said carrier arm.

10 4. In a yarn carrier for knitting machines, the combination comprising: a carrier arm having an opening adjacent an end edge thereof, a bore extending from said end edge to said opening, and a recess at at least one side of said opening; and a removable guide tube fitted in said bore with the opposite ends of said tube extending outwardly from the opposite ends of said bore, and a projection adjacent the inner tube end and fitted in said recess to preclude longitudinal movement of said tube relative to said bore, said tube being of resilient construction for at least that part of its length extending between said projection and the inner end of said bore to permit lateral flexing of said tube part for withdrawing said projection from said recess and removing said tube from said carrier arm.

15 5. In a yarn carrier for knitting machines, the combination comprising: a carrier arm having an opening adjacent an end edge thereof, a bore extending from said end edge to said opening, and a recess at at least one side of said opening; and a removable guide tube fitted in said bore with the opposite ends of said tube extending outwardly from the opposite ends of said bore, and a projection adjacent the inner tube end and fitted in said recess to preclude longitudinal movement of said tube relative to said bore, said tube being of resilient construction in the form of coiled wire for at least that part of its length extending between said projection and the inner end of said bore to permit lateral flexing of said tube part for withdrawing said projection from said recess and removing said tube from said carrier arm.

20 6. In a yarn carrier for knitting machines, the combination comprising: a carrier arm having an opening adjacent an end edge thereof, a bore extending from said end edge to said opening, and a recess at at least one side of said opening, and a guide tube having a resilient portion of coiled wire fitted in said bore with the opposite ends of said resilient portion extending outwardly from the opposite ends of said bore, and a latch-like member adjacent the inner tube end and fitted in said recess to preclude longitudinal movement of said tube relative to said bore, whereby the outer end of said tube is free to yield in event of striking an obstruction and whereby the tube is removable from said arm by flexing the inner tube end to withdraw said latch-like member from said recess and sliding said tube endwise through said bore.

25 7. In a yarn carrier for knitting machines, the combination comprising: a carrier arm having a bend adjacent an end edge thereof, an opening positioned between said bend and said end edge, a bore extending from said opening to said end edge, and recesses extending laterally of said opening adjacent the end thereof remote from said bore; and a yarn guide tube having a flexible portion of coiled wire fitted in said bore with the opposite ends of said flexible portion extending outwardly from the opposite ends of said bore, the inner end of said flexible portion

extending along said opening and having a latch-like member fitted in said recesses to preclude longitudinal movement of said tube relative to said arm, whereby the outer end of said tube is free to yield in event of striking an obstruction and whereby the tube is removable from said arm by flexing the inner tube end to withdraw said latch-like member from said recesses and sliding said tube endwise through said bore.

8. In a yarn carrier for knitting machines, the combination comprising: a carrier arm having a straight section extending a substantial part of the arm length from an end edge of said arm; said straight section having a bore extending inwardly from said end edge, a groove in substantial alignment with said bore, an eye opening between said bore and said groove, and aligned recesses extending laterally of said opening and spaced from said bore and from said groove; and a yarn guide tube having a flexible portion of coiled wire fitted in said bore with the opposite ends of said flexible portion extending outwardly from the opposite ends of said bore, the inner end of said flexible portion extending along said opening and having a latch-like member fitted in said recesses to preclude longitudinal movement of said tube relative to said arm, whereby the outer end of said tube is free to yield in event of striking an obstruction and whereby the tube is removable from said arm by flexing the inner tube end to withdrawn said latch-like member from said recesses and sliding said tube endwise through said bore.

9. In a yarn carrier for knitting machines, the combination comprising a guide tube and a carrier arm; said tube having a discharge end, a receiving end, an intermediate portion of the length thereof of resilient construction in the form of helically coiled wire, and laterally projecting means adjacent said receiving end; said arm having a bore extending inwardly of an end edge thereof, an opening at the inner end of said bore, and a recess in a face thereof, said recess being adjacent said inner bore end and extending laterally of said opening; said tube extending through said arm bore with said tube discharge end positioned beyond the outer end

of said bore and with said laterally projecting means engaging said recess to prevent endwise movement of said tube, said projecting means being adapted to be disengaged from said recess by flexing said intermediate tube portion.

5 10. For use in a yarn carrier having a carrier arm provided with a bore and a recess, a yarn guide tube comprising a resilient coiled spring tubular portion, an apertured wear-resisting tip secured to one end of said tubular member, and an element secured to the other end of said tubular member and projecting laterally therefrom, said tube being adapted to be carried by the carrier arm with an intermediate portion 15 of said tubular member fitted in said bore and with said element extending into the carrier arm recess to preclude longitudinal movement of said tube relative to the arm bore, the inner end portion of said tubular member being adapted to be flexed for withdrawing said element from the arm recess, and the outer end of said tubular member being adapted to yieldingly maintain said tip in yarn laying position beyond the carrier arm.

20 11. For use in a yarn carrier having a carrier arm provided with a bore and a recess, a yarn guide tube comprising a resilient coiled spring tubular portion, an apertured wear resisting tip secured to one end of said tubular member, and an element secured to the other end of said tubular member, said element having a pin-like shape with the opposite ends thereof extending from opposite sides of said tubular portion, having an aperture aligned with said tubular portion, and having a side thereof of arcuate shape, said tube being adapted to be carried by the carrier arm with an intermediate portion of said tubular member fitted in said bore and with said element extending into the carrier arm recess to preclude 25 longitudinal movement of said tube relative to the arm bore, the inner end portion of said tubular member being adapted to be flexed for withdrawing said element from the arm recess, and the outer end of said tubular member being adapted to yieldingly maintain said tip in yarn laying position beyond the carrier arm.

30 40 45 FRANK G. WEISBECKER.

CERTIFICATE OF CORRECTION.

Patent No. 2,317,318.

April 20, 1943.

FRANK G. WEISBECKER.

It is hereby certified that error appears in the printed specification of the above numbered patent requiring correction as follows: Page 1, first column, line 1, for "The" read --This--; and second column, line 33, after "arm" insert --end--; page 2, first column, line 8, for "slidably" read --slightly--; page 4, first column, line 31-32, claim 8, for "withdrawn" read --withdraw--; and that the said Letters Patent should be read with this correction therein that the same may conform to the record of the case in the Patent Office.

Signed and sealed this 25th day of May, A. D. 1943.
